[57] CLAIM

The ornamental design for a bird feeder, as shown and described.

DESCRIPTION

FIG. 1 is a perspective view of a bird feeder showing my new design;

FIG. 2 is a front elevational view thereof, the rear being identical to the front view shown except for the hanging hook;

FIG. 3 is a side elevational view thereof, the opposite side being identical to the side shown except for the hook;

FIG. 4 is a reduced scale bottom plan view thereof; and FIG. 5 is a reduced scale top plan view thereof.

Fig. 2
